DEEP WELL PUMP

Daniel W. Heferer, Long Beach, Calif.

Application March 14, 1938, Serial No. 195,748

2 Claims. (Cl. 103—181)

This invention relates to a deep well pump and the prime object of my invention is to provide a pump which will effectively operate in a well containing considerable quantities of sand. A feature of my invention is to provide a deep well pump with adequate packing whereby sand is prevented from settling around the moving parts, and by this means I materially prolong the useful life of the pump.

Another object is to provide a pump of the character stated which is simple in construction, effective in operation and inexpensive to manufacture.

Other objects, advantages and features of my invention may appear from the accompanying drawings, the subjoined detailed description and the appended claims.

In the drawings:

Figure 1 is a diagrammatic, longitudinal sectional view of the pump.

Figure 2 is a fragmentary longitudinal sectional view of the upper portion of the pump.

Figure 3 is a fragmentary longitudinal sectional view of the central portion of the pump.

Figure 4 is a fragmentary longitudinal sectional view of the lower portion of the pump.

Figure 5 is a sectional view taken on line 5—5 of Figure 2.

Figure 6 is a sectional view taken on line 6—6 of Figure 2.

Referring more particularly to the drawings, the numeral 1 indicates the tubing which extends from the surface of the well to adjacent the bottom thereof. Adjacent the lower end of the tubing a pipe section 2 is inserted and on the inner surface of this section a seat 3 is cut. A pump barrel 4 is positioned within the tubing 1 adjacent its lower end and this pump barrel includes a ring 5 which rests on the seat 3. A seal is thus

provided which prevents sand and fluid from passing downwardly below the seat 3 and between the tubing and the barrel. A pump plunger 6 is reciprocally mounted within the barrel 4 and closely fits this barrel through the seating

ring 5 and also at the lower end. Below the ring 5, I provide two sets of packing, preferably fibrous, although other types of packing might be used. This packing is shown at 7 and 8. The packing 7 is pressed inwardly against the plunger by a

spring 9 which bears against the top of the packing, and the packing 8 is similarly pressed against the plunger by the spring 10 which bears against the top of said packing. This packing will wipe the plunger as the plunger reciprocates, and sand

is prevented from accumulating around the

plunger due to the constant upward flow of fluid as will be further described. A standing valve 11, of usual and well known design, is mounted on the lower end of the barrel 4, a travelling valve 12, of usual and well known design, is mounted on the lower end of the plunger 6. A check valve 13 is mounted in a cage 14 on the upper end of the plunger. The valves 11, 12, 13 are all preferably of the ball type, such as are usually used in oil well pumps. A rod 15 screws into the top of the cage 14 and extends upwardly to a clutch head 16 and this clutch head in turn is threaded on to the lower end of the sucker rods 17. The rod 15 passes through a guide block 18, which screws into the upper end of the barrel 4.

The tubing 4 may be assembled from a plurality of sections and this is preferably the case, particularly since the plunger should accurately fit the inner surface of the barrel adjacent the upper end of said barrel, and particularly above the seat 3, as shown in Figure 2. The seating ring 5 is of sufficient thickness so that the plunger 6 will fit accurately within it. The seating ring 5 screws into a collar 19, the upper end 20 of which is of sufficient thickness to closely surround the plunger 6. An annular space 21 is provided above the collar 19 and between the plunger and the inner wall of the barrel. An annular space 22 is provided between the tubing 30 and the outer surface of the barrel substantially as shown in Figure 2.

A plurality of ports 23 extend through the barrel 4 above the collar 19, thus connecting the spaces 21 and 22. The purpose of these ports is to enable fluid to wash over the top of the collar 19 and prevent the accumulation of sand around the plunger at this point. On the upstroke of the plunger, fluid will be forced from the space 21 through the ports 23, thence into the space 22 and upwardly in the tubing to the surface. This rapid flow will effectively prevent the accumulation of sand at the point stated. A plurality of ports 24 are cut through the collar 19 and the solid areas between the ports 24 form fingers 25 which yieldably press against the tubing 1, for the purpose of assisting in holding the pump in position on the seat 3. This construction is termed a spring lock. The ports 24 also vent the space between the plunger and the inner wall of the collar 19 so that sand, fluid and the like can pass upwardly into the annular space 22.

Having described my invention, I claim:

1. In a deep well pump, tubing in which the pump operates, said pump including a barrel, a

hollow plunger reciprocally mounted in the barrel, a seat in the tubing, a seating ring on the barrel, said seating ring resting on the seat in the tubing, said barrel including a plurality of parts screwed together, packing arranged in the barrel below the seating ring, the lower part of the barrel having a threaded connection with the upper part of the barrel and bearing against the packing, the upper part of the barrel having a threaded connection and bearing against the packing whereby the packing is compressed, said packing bearing against the plunger.

2. In a deep well pump, tubing in which the pump operates, said pump including a barrel, a hollow plunger reciprocally mounted in the bar-

rel, a seat in the tubing, a seating ring on the barrel, said seating ring resting on the seat in the tubing, said barrel including a plurality of parts screwed together, packing arranged in the barrel below the seating ring, the lower part of the barrel having a threaded connection with the upper part of the barrel and bearing against the packing, the upper part of the barrel having a threaded connection and bearing against the packing whereby the packing is compressed, said packing bearing against the plunger, and said barrel having discharge ports above the seat through which the fluid discharged by the pump passes.

DANIEL W. HOFERER. 15
